COMMUNICATION SYSTEM

Alger S. Riggs, New York, N. Y.

Application April 29, 1933, Serial No. 668,503

7 Claims. (Cl. 179—15)

This invention relates to communication systems and more especially, though not limited thereto, to such systems as are used for the transmission and reception of telegraphic and telephonic intelligence.

An object of the present invention is the provision of a system of communication whereby a multiplicity of separate and distinct communication signals may be simultaneously transmitted over one circuit. A further object of the present invention is the provision of means for automatically maintaining synchronism between the transmitter and receiver in a communication system of the character herein disclosed.

Although I have herein shown and described but one form of my invention as applied to the transmission of a multiplicity of signals of telephonic nature, I do not limit myself thereto, inasmuch as modifications and changes may be made in the character and use of this invention without departing from the original spirit of the invention or the scope of the appended claims.

Referring to the drawings,

Fig. 1 is a diagrammatic view of one form of the present invention as adapted to the simultaneous transmission and reception of a plurality of signals of telephonic nature over one transmission line or medium.

Fig. 2 is a diagrammatic representation of the sequence-controlling apparatus and circuit as used at the transmitter.

Fig. 3 is a diagrammatic representation of the sequence-controlling apparatus and circuit as used at the receiver.

Fig. 4 is a diagram by which the mode of operation of the present invention may be readily understood.

Throughout the following, like characters are used to represent the same pieces of apparatus. Where an electron-discharge device having several internal electrodes is referred to, the characters K, G₁, G₂, G₃ and P shall refer respectively to the cathode, grid next adjacent the cathode, second grid, third grid and plate, irrespective of the normal or especial functions of such electrode.

Referring to Fig. 1, the transmitter consists of a plurality of electron-discharge devices, V₁₋₆, together with the associated apparatus hereinafter described and shown diagrammatically in the drawings to the left of the line-coupling transformer T_s. The receiver also consists of a plurality of electron-discharge devices V₇₋₁₁ together with the associated apparatus hereinafter described, and shown diagrammati-

cally on the drawings to the right of the line coupling transformer T_s.

In order to more readily understand the method of operation of the present invention, and to clearly discriminate between its mode of operation and that of conventional systems for multi-signal communication, it should be understood that in the conventional transmission or amplification of an electrical signal, the system is made to produce at its output an enlarged replica of the input signal wave form. The present invention does not contemplate transmission of the complete wave form or cycle of the signal, but of transmitting in rapid sequence, measurements of the signal voltage at spaced instants of transmission. At the receiving apparatus, the received impulses, which represent progressive and rapidly recurring or periodic amplitude measurements of the signal, each preferably of very short duration, are impressed upon a device or apparatus having appreciable relative time lag or inertia (mechanical or electrical), which may be referred to as an integrating device whereby the received impulses are in effect added or integrated into a resultant which reproduces the original wave form to a remarkable degree of accuracy. The more rapid the impulse speed with relation to the rate of change of signal characteristics (voltage), the nearer is the received and integrated signal a replica of the wave form impressed upon the transmitter and the more instantaneous the time of measurement the greater number of signal sources or programs that may be simultaneously transmitted over a single transmitting medium. By using speeds of radio frequency, a plurality of musical programs (for instance) can be transmitted over the same line or radio frequency band simultaneously.

Referring to Fig. 1, I have shown a plurality of signal sources (for example, four) connected to respective transformers T₁₋₄, the secondaries of which are connected respectively to the third grids G₃ of the tubes V₁₋₄, the plates P of which are connected together to a wire W which is also common to tubes V₅ and V₆ and is supplied with potential from source B₂ through the primary L₁ of the transformer T_s. The secondary L₂ of the transformer T_s is connected to the transmission medium, herein shown as a concentric-conductor cable line. Obviously other known transmitting media may be employed, such as a modulator of a radio transmitter.

Through means described hereinafter, the tubes V₁₋₄ are normally held inoperative and are rendered operative in rotation by the voltages sup-

plied through conductors 1-4 from the sequence selectors shown in detail in Fig. 2.

Through the medium of the voltages supplied by the sequence selector, preferably to the suppressor grids shown at G₁, the tubes V₁₋₄ are rendered operative in a predetermined sequence and deliver to the line through the transformer T₅ a series of impulses which represent the amplitudes of the respective signals upon T₁₋₄ at the instant their respective tubes are rendered operable. By using electron-discharge devices of the variety commonly known as pentode or three grid type and applying the synchronizing or "conditioning" potential to the first grids G₁, I secure from the output a signal of a fixed time interval independently of the magnitude of the signal to be transmitted. With such tubes, I effectively shield the "conditioning" and signal potentials from each other, i. e. from intra-capacity effects by the well understood action of the second grids G₂ which herein are used as screens by connecting all of said grids G₂ to a point of fixed potential such as some point in battery B₂.

Means are also provided to synchronize the receiver and sending instruments preferably through the transmitted signals themselves. To this end I provide an additional tube V₅. The tubes V₄₋₅ are preferably so interconnected that they are rendered operable during the same time interval so that their output is added but no signal is impressed upon V₅ and hence it delivers to the line an impulse of constant magnitude (preferably greater than any of the tubes V₁₋₄) which is intercepted at the receiving device for the purpose of indexing or controlling the sequence-selector S' at the receiver.

The impulses transmitted, therefore, may be represented by the diagram of Fig. 4, the rectangle 1' representing an impulse from tube V₁, rectangle 3' an impulse from tube V₃, 2' representing the same from the tube V₂, and 4' representing the combined impulses from tube V₅ (represented by the shaded portion of the rectangle 4', and the unshaded portion added by tube V₄). The amplitude of the impulses from tubes V₁, V₂ and V₃ never rises above dotted line 6, which lies below the top of the shaded portion of rectangle 4', shown by line 7.

The series of signal impulses received by the transformer T₆ are impressed upon the third grids G₃' of tubes V₇₋₁₀, which are biased with respect to the several cathodes by battery B₃, and upon the plate or anode P' of the tube V₁₁.

Through the medium of the sequence-selector S', shown in Fig. 3, the tubes V₇₋₁₀ are rendered operable in regular and synchronized sequence at such instants as to permit the respective tubes to deliver a signal impulse in its output circuit which is proportional to the original signal impressed upon the corresponding tube at the transmitter. The rapid radio frequency signals from each tube are impressed on their respective transformers T₇₋₁₀, but said transformers possess sufficient electrical inertia so that they respond only to the main variations in the output of the tubes. In other words, the transformers act to integrate or smooth out the rapid spaced signals into audio frequency signals. Thus the transformers T₇₋₁₀ each deliver a separate signal corresponding to those impressed upon the transmitter successively through tubes V₁₋₄.

The tube V₆ at the transmitter and the tube V₁₁ at the receiver serve the function of preventing surge voltages respectively across L₁ and L₄ by quick quenching of the secondary oscilla-

tions. The transmitted and received impulses are prevented by tubes V₆ and V₁₁ from becoming positive with respect to the respective cathodes of said tubes so that only voltages of the desired polarity exist across L₁ and L₄, respectively. 5

Tubes V₆ and V₁₁ are, in effect, connected across primary L₁ of transformer T₅ and secondary L₄ of transformer T₆ respectively. In the former case, the anode of tube V₆ is connected to the anodes of tubes V₁₋₅; the screen grid of tube V₆ is biased by connection to battery B₂; and the other grids and the cathode in the tube are connected in common to the cathodes of tubes V₁₋₅. Thus, the tube V₆ affords a 15 by-pass for surges in the system which would otherwise increase the positive potential of the plates of tubes V₁₋₅ and increase the currents therethrough, to the detriment of the operation of the system. At the receiving end, the anode 10 of tube V₁₁ is connected to the grids of tubes V₇₋₁₀, the screen grid of tube V₁₁ is biased by connection to battery B₄; and the other grids and the cathode are connected in common to the cathodes of tubes V₇₋₁₀. Thus, the tube V₁₁ affords a 15 by-pass for surges in the system which would otherwise make the control grids of tubes V₇₋₁₀ positive with respect to their cathodes, and, therefore, increase the currents through those tubes. Surge voltages of opposite sign are suppressed at opposite ends of the system. Thus, 20 surge voltages which are negative with respect to the transmitter are positive with respect to the receiver and are by-passed at the receiver, and vice versa. 35

Referring now to Fig. 2, the selector generator E and sequence-selector S used at the transmitter consist of the tubes V₁₂₋₁₄. The tube V₁₂ together with the multi-wound transformer T₁₁ operates as a generator of sinusoidal voltage 40 waves which are impressed upon the resistance R₁ and the variable condenser C₁. Winding L₈ thereof serves as the main "tank" circuit of the generator, while L₆ serves as feed-back grid excitation of the tube V₁₂. The inductance (secondary) L₇ completes the output of the generator to the load R₁ and C₁. The voltages respectively across R₁ and C₁ are impressed upon the tubes V₁₃₋₁₄ of sequence selector S, and since these voltages are in quadrature relation the transformers 45 T₁₂₋₁₃ supply to their respective terminals amplified voltages having quadrature relation. The terminal wires 1-4 connect respectively to the first grids G₁ of the tubes V₁₋₅ and the terminal wire 5 connects to the common cathode return of the tubes V₁₋₅. The rectifying action of the tubes produces a direct current voltage across resistance R₃ and condenser C₂ of the polarity shown which effectively renders the tubes inoperable except during the period when the grids 50 have impressed thereon substantially the peak voltage in the positive direction. A second resistance R₂ may be used to effectively filter the rectified voltage above referred to. 55

Referring now to Fig. 3, the tubes V₁₇₋₁₈, transformers T₁₅₋₁₆, and their respective terminal wires 6-9 connect to the first grids G₁' of the tubes V₇₋₁₀, and the terminal wire 10 is connected to the common point of the cathodes K' of tubes V₇₋₁₁. The terminal wires 11 and 12 connect 60 across the secondary L₄ of the transformer T₆, and therefore, all voltage impulses are impressed upon the first grid of the tube V₁₅. The receiving selector generator E' comprises the tube V₁₅ and associated circuits which constitute a dyna- 70 75

tron oscillator arrangement operating under the control of the incoming impulse from tubes V₄₋₅. The plate of tube V₁₅ is connected to a source of potential B₅ and one of the auxiliary grid electrodes of the tube V₁₅ is charged at a higher potential than the plate by a portion of the source of potential B₆. The tube V₁₅ then will oscillate due to the well known phenomenon of secondary electron emission. This operation of the tube 5 V₁₅ is reinforced once every cycle by the extraordinary impulse transmitted through tubes V₄₋₅, and impressed on the control grid of tube V₁₅ through conductor 12, thus maintaining synchronism in the system. The other impulses transmitted through tubes V₁₋₃ are of insufficient magnitude to exert any control upon the oscillator V₁₅. The output wave of the oscillator V₁₅ is impressed directly on the control grid of amplifier tube V₁₆, the output circuit of which is tuned to 10 resonance with the frequency of the oscillator V₁₅ which is synchronized with and, therefore, equal to the frequency of the oscillator V₁₂ at the transmitter.

Transformer T₁₄, comprising inductive elements L₁₂ and L₁₃, couples the oscillation from the receiving selector generator E' to the sequence selector circuits shown generally at S'. The secondary L₁₃ is connected to tubes V₁₇ and V₁₈ through resistance and condenser elements in 15 such a manner that tubes V₁₇₋₁₈ operate in quadrature relation.

The variable resistances R₅ and R₇ and the variable condenser C₃₋₄ permit of adjustment of the relative phases of the voltages impressed upon 20 the tubes V₁₇₋₁₈ in order that the proper sequence of operation may be secured in the tubes V₇₋₁₀.

The resistance R₈ serves to render the voltage across secondary L₁₃ of transformer T₁₄ independent of the adjustments of C₃₋₄ or their respective 25 resistances, and the resistances R₈₋₉ and the condenser C₅ serve at the receiver the same functions as those of R₂₋₃ and C₂ at the transmitter. The output transformers T₁₅ and T₁₆ correspond 30 in connection and function with the transformers T₁₂ and T₁₃ in the sequence selector S in the transmitter. The tubes V₇₋₁₀ are, therefore, actuated in synchronized sequence through conductors 35 6-9 connecting to the actuating grids G_{1'} in the tubes V₇₋₁₀. Meanwhile, the incoming signal energy is continually being impressed upon control grids G_{2'} of the tubes V₇₋₁₀, and as the tubes are sequentially actuated, the signal impulses are selectively transmitted to the output transformers T₇₋₁₀ which act, by virtue of their inertia, to 40 smooth out the signal impulses into a substantially true reproduction of the signal.

In accordance with the provisions of the patent statutes, I have herein described the principle and operation of my invention, together with the 45 apparatus which I now consider to represent the best embodiment thereof, but I desire to have it understood that the apparatus shown is only illustrative and that the invention can be carried out by other means. Also, while it is designed to use the various features and elements in the combination and relations described, some of these 50 may be altered and others omitted without interfering with the more general results outlined, and the invention extends to such use.

Having described my invention, what I claim and desire to secure by Letters Patent is:

1. In an apparatus for receiving and rendering intelligible a multiplicity of continuous signals, a common input circuit, an electron-discharge device connected thereto and responsive only to sig- 55

nals of greater amplitude than the average maximum amplitude, a plurality of other normally inoperative electron-discharge devices, one for each of the received signals, and selective means controlled by said first-named device for rendering said last-named devices sequentially operative. 60

2. The method of transmitting a multiplicity of signals which consists in transmitting in sequence high frequency amplitude measurements of all of said signals and superimposing on each 10 recurring measurement of one only of said signals a fixed amplitude indication for synchronizing a receiving device with the transmission sequence.

3. In a multiplex communication system, a transmitter including a plurality of signal input 15 circuits, an electron tube individual to each of said signal input circuits, said electron tubes each including a cathode, an anode, and a plurality of grid electrodes, a connection between each of said signal input circuits and one of said grid electrodes in each of said electron tubes, means for generating a recurring series of impulses of positive polarity by effecting a multiplicity of different phase relations within each cycle of generated voltage, a connection between said means 20 and another of the grids of each of said electron tubes for impressing a positive potential upon the said grids in successive order, a common output circuit connected between the plate and cathode of each of said electron tubes, a communication 25 circuit, a connection between said common output circuit and said communication circuit whereby signal energy impressed upon said signal input circuits is successively transferred to said communication circuit in recurring time intervals at 30 a rate determined by the positive potential impulses upon the said grids of said electron tubes, and means for periodically superimposing a synchronizing impulse upon the output of one of said tubes in said communication circuit in step with 35 said recurring time intervals.

4. In a multiplex communication system, a transmitter including a plurality of signal input circuits, an electron tube individual to each of said signal input circuits, said electron tubes each including a cathode, an anode, and a plurality of grid electrodes, a connection between each of said signal input circuits and one of said grid electrodes in each of said electron tubes, an oscillator circuit, means for producing a series 45 of impulses of positive polarity from each cycle of oscillation of said oscillator circuit, a connection between said means and another of the grids of each of said electron tubes for impressing a positive potential upon the said grids in successive 50 order, a common output circuit connected between the plate and cathode of each of said electron tubes, a communication circuit, a connection between said common output circuit and said communication circuit whereby signal energy impressed upon said signal input circuits is successively transferred to said communication circuit in recurring time intervals at a rate determined by the positive potential impulses upon the 55 said grids of said electron tubes, and means for periodically superimposing a synchronizing impulse upon the output of one of said tubes in said communication circuit having an amplitude of positive potential which is greater than the maximum amplitude of the output of the others 60 of said electron tubes.

5. In a multiplex communication system, a transmitting system comprising more than two signal input circuits, an electron tube circuit individual to each of said signal input circuits, a 65

- common output circuit connected with all of said electron tube circuits, a communication circuit connected with said output circuit, an oscillator circuit, a sequence selector connected with said oscillator circuit for producing successive conditioning impulses for said electron tube circuits, means for periodically impressing an impulse upon the output of one of said electron tube circuits having an amplitude exceeding the maximum amplitude of the output of the others of said electron tube circuits, a receiving system connected with said communication circuit, electron tubes connected with said receiving system and corresponding in number to the number of signal input circuits in the transmitting system, a sequence selector in said receiving system, and means for controlling said sequence selector by the said impulse of excessive amplitude for successively conditioning each of the electron tubes in said receiving system for independently receiving signal energy impressed upon the signal input circuits in the transmitting system.
6. In a multiplex communication system, a receiving system comprising a multiplicity of electron tubes corresponding in number to the number of signal channels which may be impressed upon said receiving system, a sequence selector,

and means controlled by a synchronizing impulse of fixed magnitude periodically received simultaneously with the signals in one of said signal channels for actuating said sequence selector for rendering said electron tube circuits successively effective for independently and sequentially responding to successive groups of recurring signal impulses. 5

7. In a communication system for the transmission of more than two separate signals over 10 a common transmitting medium which includes a transmitter that produces a series of periodic potentials from each cycle of a single actuating oscillation, which signals are transmitted under control of the said periodic potentials and a receiver which produces a corresponding series of periodic potentials, the method of synchronizing the operation of the transmitter and the receiver which comprises superimposing on the measurements of one of the signals at the transmitter an impulse of constant amplitude, and impressing the said constant amplitude impulse on the means for producing the series of periodic potentials at the receiver whereby the said periodic potentials are produced in synchronism with those produced 15 at the transmitter. 20 25
